5 Claims. (Cl. 29—200)

This invention is a specialized machine for removing 10 scrap parts from gaps in zipper strips.

The zipper strip for which the invention is intended has a pair of tapes with interengaged fastening elements of the coil filament type attached thereto. The strip, prior to the operation of the present machine, has previously been provided with gaps at spaced intervals where the head portions of a plurality of the engaged coil convolutions have been cut away leaving a length of chain between such gaps which will correspond to the length of zipper that is desired. This first operation leaves substantial scrap parts still attached to the tapes. These are called the heel portions of the coils as distinguished from the head portions. It will be understood that the strip is cut across the gaps making up individual zippers and if these heel portions are left in place, they will obviously be objectionable in the finished zipper. It is especially important that they be removed in fasteners which are to be equipped with separating bottom stops.

In accordance with the invention, the machine removes these scrap portions of the coils by a single direct movement of a carriage along the strip while the strip is held in a definite position with a blade extending into the gap which has been previously cut.

Other objects and advantages of the invention will hereinafter more fully appear.

In the accompanying drawings, I have shown for purposes of illustration, one embodiment which the invention may assume in practice. In these drawings:

FIG. 1 illustrates a portion of a continuous zipper strip for which the invention is adapted;

FIG. 2 is a top plan view of the machine;

FIG. 3 is a front elevation of the principal portions of the machine;

FIG. 4 is a right end elevation of the machine;

FIG. 5 is a detailed cross-sectional on line 5—5 of FIG. 2;

FIG. 6 is a detailed lengthwise section on line 6—6 of FIG. 2;

FIG. 7 is a cross-section on line 7—7 of FIG. 2;

FIG. 8 is a detailed section of the stripper finger turret unit taken on line 8—8 of FIG. 2;

FIG. 9 is an exploded view of one of the turret and tool mountings;

FIG. 10 is a detailed section on line 10—10 of FIG. 2;

FIG. 11 is a diagrammatic view illustrating the stripping action; and

FIG. 12 is a perspective view of the positioning blade.

The zipper strip, as best seen in FIGS. 1 and 11, has a pair of tapes T with fastener elements C of the coil filament type attached thereto. The coils are interengaged by their head portions, except for gaps 11 at spaced intervals. These gaps have been previously formed by cutting away the head portions leaving the heel portions 12 as scrap firmly attached to the tapes where they are normally held by stitching S which is partially indicated in FIG. 11.

The machine rests upon a bed 13 in the form of an elongated block of generally rectangular cross-section. This bed may be mounted for lengthwise adjustment upon a rail 14 and the bed may be clamped to the rail in any adjusted position by hand-operated screws 15. The rail

2

14 may be carried by suitable support brackets 16 at either end.

The carriage, which includes the block 17, is mounted over the bed—for longitudinal sliding movement and for pivotal movement—so that it can be lifted away from the bed to arrange the zipper strip. For this purpose, the carriage block 17 is securely fastened to a guide rod 18 as by means of a stud 19 which is seen in dotted lines in FIG. 2. The guide rod can freely slide and rotate in a bearing block 20 which is rigidly secured to the bed by suitable bolts 21. This bearing block 20 also acts as a stop to limit movement of the carriage toward the left. Movement of the carriage in the other direction is limited by a stop block 22 which is rigidly held to the bed 13 by a screw 23. This screw extends through an elongated slot 24 shown in dotted lines in FIG. 2, so that the stop can be adjusted lengthwise of the bed. A recess shown in dotted lines in FIG. 2 is for the purpose of accommodating the stud head 19. While the back portion of the carriage 17 is supported by the guide rod 18 in a cantilever fashion, the front portion rests upon a narrow bearing surface 25 which is at a slightly higher level than the main portion of the bed 13 to provide a slot 26 for the tapes T of the zipper strip. When the carriage is in its closed or operating position as shown in FIG. 7, it is held by a latch 27 fitting in a slot 28 in the carriage block and pivoted on a pin 29. It is normally held in latched position by a coil spring 30, and a stop pin 31 may be provided to prevent overtravel of the latch. The hook end 32 of the latch rides in a groove 33 in the bed 13 and to prevent excessive wear, a wear plate 34 may be provided.

On the carriage block 17 and in side-by-side relation are secured the turret mounting blocks 35 and 36 and they are adjustably fastened by studs 37 and 38 passing through longitudinally extending slots 39 in the turret blocks. This adjustment can be accurately regulated by screws 40 extending through the depending lugs 41 and into the carriage block 17, as seen in FIG. 6.

At the forward end of each of the mounting blocks 35 and 36 are the turrets 42 which are of like construction; one of them is shown in detail in FIGS. 8 and 9. Each turret 42 is a cylindrical shell fitting in a cylindrical recess 43 in the top face of the turret mounting block 35, angularly adjustable about a vertical axis and is held in any desired adjusted position by a set screw 44. Each turret carries a tool holder in the form of a cylindrical post 45 which is adjusted vertically by a screw 46 having threaded engagement with the post 45, but not with the turret 42. The end of the screw 46 abuts against the bottom of the recess 47 in the turret to determine the vertical position of the post whereupon it can be locked in such position by the locking screw 48 which has threaded engagement with the turret, but not with the post and it will abut the bottom of a recess 49 in the post so as to lock it in the desired adjusted position. This particular detail is a known form of tool adjustment and need not be further described.

The posts 45 carry the stripping fingers 50 and 51 which extend into drilled holes in the posts and may be adjusted inwardly and outwardly of the post and held by set screws, one of which is seen in FIG. 6 to 52. These fingers are mounted at an acute angle to the center line of the zipper strip; in other words, they project forwardly and downwardly into the line of the heel portions 12. In this position, when they are moved by the carriage, they will hook into the heel portions 12 and pull them away from the tapes as represented in FIG. 11.

For the purpose of lifting the carriage when the latch 27 is released, and also for pulling the carriage along the bed, there is provided a suitable handle 53. It will also be noted, especially in FIG. 7, that the undersurface of

the carriage block 17 has a groove 54 with sloping side surfaces for snugly receiving the interengaging coils C of the zipper strip. There may also be a groove 55 which, when the carriage is moved forward, can accommodate the positioning blade 56. This blade has a comparatively thicker and longer base portion 57 with a curved bottom edge which is secured in a suitable recess of the bed 13 by means of a screw 58, as seen in FIGS. 3 and 10.

The upper portion 59 of the positioning blade 56 is made to a predetermined length equal to the length of the gap where the head portions of the coils have been cut away. The blade 56 may be easily removed and replaced to accommodate gaps of different lengths.

Referring now to FIG. 10, the thickness of the upper portion 59 of the positioning blade 56 is at least as much as the normal spacing between the bottom legs 60 of the scrap portions 14, so as to position these scrap portions in a definite alignment. In the cutting operation, prior to the use of the present machine, the cutting blade will have left a somewhat wider gap between the upper portions of the scrap parts 14 and will have left the edges of the tapes T intact. When the zipper strip is placed over the positioning blade 56, there might be a tendency for the tape edges to crowd between the portions 60 of the scrap parts and the blade 56. This would interfere with the accurate lateral positioning of the scrap parts preparatory to stripping. To avoid this, the bed 13 is slightly undercut or grooved on opposite sides of the blade 56 as indicated by the numeral 61.

In operation, the zipper strip may come from any suitable continuous source, such as a roll, or it may come directly from the machine which has cut away the head portions of the coils. In any case, some means should be provided to create tension on the strip as it moves to the machine. For this purpose, I have indicated upper and lower rollers 62 and 63, respectively, which can grasp both of the tapes T. If one or both of these rollers is controlled by a suitable friction clutch, it will obviously be necessary to place tension on the strip to pull it into the machine.

To place the strip in proper position for the stripping operation, the latch 27 is released from groove 33, the carriage swung upwardly while supported by the guide rod 18. This enables the operator to pass the projecting portion 59 of the positioning blade through a gap in the strip. Then the operator, making certain that the carriage block 17 is abutted against the stop 22, will swing the carriage down so that it bears on the surface 25 and the latch 27 will automatically snap into the groove 33. This will bring the pointed ends of the stripping fingers 50 and 51 into stripping position where they will hook into the heel portions 14 which constitute the scrap to be removed. Then the operator, grasping the handle 53, moves the carriage along the bed with the guide rod 18 sliding in the bearing 20, and the latch 27 sliding in the groove 33. This is a straight line action parallel to the direction of the strip so that the stripping fingers will pull the scrap portions 14 away from the stitches S where they may fall away or be removed by an air blast.

The opposite sides of the zipper strip are firmly held against endwise movement during the stripping action by the blade 56, the forward end of which as seen at 64, is abutted against the interengaged head portions at one end of the gap. It will be understood also that in the stripping process, some tension may be applied to the lead end of the strip either manually or mechanically.

The stripping operation can be successfully performed only if the stripping fingers are accurately positioned in various ways. It will be noted that there is provided independent lengthwise adjustments by means of screws 40 between the mounting blocks 35 and 36 and the carriage block 17. Vertical adjustment of the tool holders in the mounting blocks is provided by the screws 46 and 48. Angular adjustment of the tool holders is permitted by the cylindrical turret 42 and the cylindrical re-

cess 43 in each of the mounting blocks. Finally, endwise adjustment of each stripping finger 50 relative to the tool holder, is accomplished by positioning it in the hole of the tool holder and anchoring the same by the screw 52.

While the form of the invention herein shown and described embraces a preferred embodiment of the same, it is to be understood that the construction may be varied as to mechanical details without departing from the spirit of the invention and the scope of what is claimed.

What I claim is:

1. In a machine for removing scrap parts from a zipper strip which consists of a pair of tapes having interengaged fastening elements of the coil filament type attached thereto with gaps provided at spaced intervals where the head portions of a plurality of coil convolutions are cut away leaving the heel portions as scrap parts attached to the tapes, the combination of
  - (a) a supporting bed for the zipper stringer;
  - (b) a blade-like positioning member projecting upwardly from said bed and dimensioned to fit snugly in one of said gaps;
  - (c) stripping fingers on opposite sides of said blade having pointed ends adapted to hook into said heel portions;
  - (d) means for rigidly mounting said fingers so that their pointed ends project into the line of said heel portions; and
  - (e) said mounting means being movable relative to said bed and blade in a direction lengthwise of the zipper strip to remove the scrap parts along said gaps.
2. The combination defined in claim 1, together with stop means to limit the relative movement between said fingers and blade so that the pointed ends of said fingers move only over the length of a gap through which said blade projects.
3. In a machine for removing scrap parts from a zipper strip which consists of a pair of tapes having interengaged fastening elements of the coil filament type attached thereto with gaps provided at spaced intervals where the head portions of a plurality of coil convolutions are cut away leaving the heel portions as scrap parts attached to the tapes, the combination of
  - (a) a supporting bed for the zipper stringer;
  - (b) a blade-like positioning member projecting upwardly from said bed and dimensioned to fit snugly in one of said gaps;
  - (c) a carriage mounted on said bed for slidable movement lengthwise of said bed and said zipper strip; and
  - (d) stripping fingers rigidly mounted in said carriage, one on each side of said blade, said fingers having pointed ends projecting between said heel portions and at an acute angle to the center line of the zipper strip so as to hook into said heel portions and remove them from the tapes upon rectilinear movement of said carriage.
4. In a machine for removing scrap parts from a zipper strip which consists of a pair of tapes having interengaged fastening elements of the coil filament type attached thereto with gaps provided at spaced intervals where the head portions of a plurality of coil convolutions are cut away leaving the heel portions as scrap parts attached to the tapes, the combination of
  - (a) a supporting bed for the zipper stringer;
  - (b) a blade-like positioning member projecting upwardly from said bed and dimensioned to fit snugly in one of said gaps;
  - (c) a carriage mounted on said bed for slidable movement lengthwise of said bed and said zipper strip;
  - (d) a pair of mounting blocks attached to said carriage and adjustable lengthwise of the zipper strip;
  - (e) a tool holder on each of said mounting blocks and adjustable vertically therein with respect to said zipper strips; and

(f) stripping fingers attached to said tool holders in such positions that the ends of said fingers extend between said heel portions.

5. The combination defined in claim 4 wherein said tool holders are also adjustable angularly about a vertical axis and wherein said stripping fingers are adjustable in said tool holders inwardly and outwardly of said heel portions.
